United States Patent Office.

WILLIAM WEISNER, OF ELIZABETHTOWN, NEW MEXICO TERRITORY,
ASSIGNOR TO HIMSELF AND CLAUDIUS KIEFER.

Letters Patent No. 99,039, dated January 18, 1870.

IMPROVEMENT IN STRIKES FOR LOCKS.

The Schedule referred to in these Letters Patent and making part of the same.

To all whom it may concern:

Be it known that I, WILLIAM WEISNER, of Elizabethtown, in the county of Colfax, and Territory of New Mexico, have invented a new and improved Strike for Mortise-Locks; and I do hereby declare that the following is a full, clear, and exact description thereof, which will enable others skilled in the art to make and use the same, reference being had to the accompanying drawings, forming part of this specification.

This invention relates to improvements in strikes for mortise-locks or sliding bolts, and consists in the combination, with the said strikes, as commonly used, of plates, arranged in the mortises, to close the same when the bolt is withdrawn, to present a more ornamental appearance, and to prevent the mortises from filling up by collections of dust and other matter.

Figure 1 represents a front elevation of my improved strike, and

Figure 2 represents a section of the same, taken on the line *x x* of fig. 1.

Similar letters of reference indicate corresponding parts.

A is the strike, such as commonly used with mortise-locks, or for sliding bolts for folding doors, drawers, chests, and the like.

As before stated, my invention consists in the combination, with these strikes, of plates B, journaled at one end in lugs C, at the rear side of the strikes, and arranged so that when the bolts are withdrawn, they will swing into the mortise and close the same, so that while the door is open and the strike exposed to view, it will present a neater appearance.

The said plate B also excludes the dust and other

matter which usually collect in the mortises, when exposed in the common way.

This plate B may be arranged to swing into the closing position by the action of gravity, when the strike is placed in vertical or overhead walls, but when placed in the floor, it requires a spring or a counter-balance-weight to close it.

The arrangement which I prefer is a spring, D, coiled around a curved arm, E, fixed to the strike A, and another curved arm, F, fixed to the swinging plate B, the one, E, being slotted or grooved, and the other fitted to work in the slot or groove of the arm E, and the spring arranged to press each plate.

The arms, however, may be dispensed with, and flat springs used in place of the said arms and the coiled spring.

The lock-bolts or sliding bolts press the plates back when shot.

Having thus described my invention,

I claim as new, and desire to secure by Letters Patent—

The combination, with the strike for a mortise-lock or sliding bolt, of a plate, B, hinged thereto, and arranged to swing into the mortise, to close the same, when the bolt is withdrawn, and to be operated for closing either by springs or by gravity, substantially as specified.

The above specification of my invention signed by me, this 14th day of September, 1869.

WILLIAM WEISNER.
